WATSON SANFORD, OF NEW YORK, N. Y.

Letters Patent No. 97,967, dated December 14, 1869; antedated September 15, 1869.

BASE-BURNING STOVE.

The Schedule referred to in these Letters Patent and making part of the same

To all whom these presents shall come:

Be it known that I, WATSON SANFORD, of the city, county, and State of New York, have invented certain new and useful Improvements in Stoves; and I do hereby declare the following to be a full, clear, and exact description thereof, reference being had to the accompanying drawings, and to the figures and letters marked thereon.

Of these drawings—

Figure 1 is an elevation of my improved stove,
Figure 2, a vertical central section,

Figure 3, a plan view, and

Figures 4 and 5 are horizontal sections at *xx* and *yy* of fig. 1.

My improvements relate—

First, to the construction of the upper part of the coal-receiver or chute.

Second, in the arrangement of an adjustable passage-way immediately above and to the chute, in order to permit of the easy removal and replacement of the latter.

Third, in the arrangement of divisional strips or partitions, placed between the chute and the outer casing.

Fourth, in the arrangement of a horizontal slide-damper under the escape-pipe, and about midway between the top and bottom of the chute.

Fifth, in the arrangement of the grate, so as to permit of its being easily removed.

Sixth, in attaching and arranging the foot-ring.

To enable those skilled in the art to construct and use my improvements, I will proceed to describe their construction and operation.

a is the chute or coal-receiver, for a short distance on the upper portion of which I construct the open or basket-work *b*.

There is placed at the base of this open-work, within the chute, a narrow rim, and a cover thereon, as shown at *b'*, by reason whereof I am enabled to use a portion of the upper part of the chute as a means of communication with the escape-pipe. This also serves to lessen and prevent the explosion of gases in the coal-receiver. This has been troublesome and annoying in this class of stoves, as when such gases accumulate in the chute, they become fixed, and explode, thereby frequently injuring the stove. By reason of this invention, such gases will throw up the inner cover *c*, and pass off through the open-work, into the escape-pipe *d*.

e is a rim or ring, taking up a portion of the top of the stove, which rim is made wide enough, so that when removed from the top, it forms an opening at *e*, in direct contact with and of larger diameter than the chute, and which will permit of the ready withdrawal of the chute.

This rim is held in place by resting on, and being fastened with iron or wire bolts down to, the lugs *f*, *f*,

&c., projecting from the inside of the top portion of the stove, *g*, within which this rim fits. This is of great importance, if it is desired to get at the coal-chute in order to repair or clean it. Heretofore, the repairing has been done at much trouble and expense.

h h are metal strips, or divisional plates, which are of the width of the passage or circular flue between the chute and body of the stove, fastened at their lower extremities to a horizontal strip, *i*, dividing horizontally the back part of this whole passage-way.

These strips extend up two-thirds of the way to the top of the stove, or more, and are constructed so that an additional piece placed on each, made in an angular shape or in a slide form of construction, can be moved up and down, so as to increase or decrease the length of the division-plate, and thus render more or less effective the throwing of the heat to the front or rear of the stove; or it can, by means of a slide-damper, *j*, in the horizontal strip or division-plate *i*, be left free to pass up equally around the body of the stove.

The vertical division-plates can be left single, that is to say, not adjustable, if desired. These being also screwed down to the plate *i*, as shown at *k k*, admit of their easy removal for packing separately, thus avoiding breakage.

j is a slide-damper in plate *i*, containing several openings, and its arrangement at this point of the chute will admit of direct draught from the fire to the smoke-pipe, at the time of kindling the fire, which, with the aid of the division-strips, mainly confines the products of combustion to the back of the stove, as in a chimney; then, after the thorough ignition of the fuel, the heat can be thrown mainly to the front part of the stove by closing this damper.

m is a slot in the rim *m'*, containing the sockets for the grate-bar, through which slot can pass the projection *n*, on the grate, thus enabling the grate, when such projection is opposite the slot, to be let down and removed away, by reason of one of the trunnions passing out of its socket, such socket being cut away on its front side, as shown at *n'*. This is of great convenience, in case of removal, required for cleaning or repairs.

o is the fire-pot, which, in this class of stoves, has been heretofore cast in sections, and where the heat has been intense, the sections have opened, thus permitting gases and dust to escape. The brick being laid solid in this bowl, and angular, and to the shape of it, admit of a direct and intense radiation of heat down to those portions of the floor immediately at the base of the stove.

p is a foot-ring, which is in position about on a line with the top of the fire-chamber, and is attached to brackets, *q q q*, which take into slots placed on the under side of the ring.

The horizontal portions of the brackets are fitted to

a small rim, r , cast around the stove, almost in the same horizontal plane as the foot-rest. The other arms of the brackets rest down on the stove, at or near the lower part of the fire-pot. These improvements all tend to render more effective this class of stove, and their respective features of utility are apparent.

What I claim as new, and desire to secure by Letters Patent, is—

1. The arrangement of open-work at the upper portion of the chute, substantially as described.

2. The arrangement of an additional opening or passage-way to the chute, and in direct contact therewith, and of larger diameter, to admit of a more convenient withdrawal or replacement of such chute, substantially as described.

3. The arrangement of divisional plates or strips

longitudinally between the chute and body of the stove, substantially as described.

4. Making such divisional plates or strips adjustable, substantially as described.

5. The arrangement of a slide-damper horizontally between the chute and body of the stove, substantially as described.

6. The construction of the grate and rim containing the trunnions, to admit of the removal of the grate, substantially as described.

7. The arrangement of the foot-ring, when combined with the brackets q q , substantially as described.

WATSON SANFORD.

A. B. MALCOMSON, Jr.,

JAMES H. HUNTER.
